TAPE LINE WIPER

Carl C. Taylor, Garland, Tex.

Application August 30, 1954, Serial No. 32,088

Term of patent 7 years

(Cl. D9—6)

Fig. 1.

Fig. 2.

Fig. 5.

Fig. 6.

Fig. 3.

Fig. 4.

Fig. 1 is a side elevational view of the tape line wiper showing my new design, as mounted on a tape being wiped, the latter is shown in broken lines for purposes of illustration.

Fig. 2 is a top plan view of my line wiper.

Fig. 3 is a side elevational view thereof.

Fig. 4 is a bottom plan view thereof.

Fig. 5 is a right-end elevational view thereof.

Fig. 6 is a left-hand elevational view thereof.

I claim:

The ornamental design for a tape line wiper, substantially as shown and described.
